UNITED STATES PATENT OFFICE

WILLARD E. ERICKSON, OF CHICAGO, ILLINOIS, ASSIGNOR TO LINK-BELT COMPANY,
OF CHICAGO, ILLINOIS, A CORPORATION OF ILLINOIS

ROTARY CAR DUMPER

Application filed November 5, 1928. Serial No. 317,372.

My invention relates to improvements in car dumpers and has for one object to provide a new and improved car dumper and clamping means therefor. Another object is to provide a car dumper wherein the clamps are supported on the dumping side of the cradle and wherein the clamp supporting and operating mechanism are protected nevertheless from interference and clogging by the dumped material. Another object is to provide a take-up mechanism which will contain the holding and lifting ropes tight at all times independent of the structure. Other objects will appear from time to time throughout the specification and claims.

My invention is illustrated more or less diagrammatically in the accompanying drawings, wherein—

Figure 1 is an end elevation with parts in section;

Figure 2 is a section along the line 2—2 of Figure 3;

Figure 3 is a section along the line 3—3 of Figure 2;

Figure 4 is a section similar to Figure 2 showing the cradle in the dumping position;

Figure 5 is a detail;

Figure 6 is a section along the line 6—6 of Figure 5;

Figure 7 is a detail side elevation;

Figure 8 is a detail of the equalizing mechanism;

Figure 9 is a detail of the counterweight.

Like parts are indicated by like characters throughout the specification and drawings.

A is a foundation of concrete, masonry or similar material. It contains a receiving hopper A¹ into which the car to be dumped is discharged. Mounted on the foundation and bridging the hopper in part is a supporting frame structure A², there being one at either end of the hopper.

Pillow blocks A³ A³ are mounted on this frame-work A² and pivoted on these blocks are roller equalizing levers A⁴ each lever carrying two rollers A⁵ pivoted at each end thereof. A⁶ A⁶ are roller rings, one mounted on each two pairs of rollers A⁵. These roller rings are joined by the cradle frame-work A⁷ and the rollers and frame-work form the

cradle and are mounted for rotation in unison.

A⁸ A⁸ is a cable, there being one for each roller ring. This cable is wound about the roller ring, being dead ended on each end on spring-held tension rods A¹⁸ sidable in lugs A⁹ on the roller rings. The bight of the cable is wound about a driving sheave A¹⁰, there being one driving sheave at each end of the machine. A shaft A¹¹ carries both driving sheaves and is driven by means of a train of gears contained within the gear casing A¹² by an electric motor also contained within the casing. A¹³ is a solenoid brake which operates in the usual manner to lock the shaft A¹¹ against rotation when the power is turned off the motor so that the cradle is always locked in whatever position it is left by the motor.

B is a transfer table contained within the cradle. This transfer table is provided with rollers B¹ B¹ traveling upon tracks B² in the cradle so that the transfer table may move laterally. B³ B³ are abutments, one at each end of the cradle on the foundation adapted to be engaged by rollers B⁴ on lugs B⁵ one at each end of the transfer table. B⁶ B⁶ are compression springs interposed between the cradle and the transfer table tending to move the cradle toward the left as shown in Figure 1 to bring the car B⁷ on the tracks B⁸ on the transfer table against the cushion B⁹ on the side of the cradle. It will be understood that when the cradle is in the central loading position as shown in Figures 1 and 2, the engagement of the roller B⁴ with the stops B⁵ centers the transfer table compressing the springs B⁶, whereas when the car is in the dumping position, the movement of the cradle from the loading toward the dumping position in a counter clockwise direction permits the spring B⁶ to force the transfer table to the left at the beginning of the movement before the clamps which hold the car in place have been seated.

Located along the side of the cradle, where material dumped from the car flows, which we prefer to refer to as the down-stream side of the cradle, are a series of vertical guide columns C C, there being preferably four of

these though there may be more or less as the case may be. On the opposed side are somewhat similar guide columns C¹. Slidable along each of the guide columns C are 5 a series of clamps. A description of one of these suffices for all since they are identical. Each clamp comprises a relatively elongated sliding carriage member C² extending down along the guide column C having at its upper 10 end a pivot C³ upon which is pivoted a clamp member C⁴, there being a sheave C⁵ concentric with each pivot C³. Each clamp member C⁴ has at its outer end a sheave C⁶ and a stirrup C⁷ which engages the guide column C¹ 15 through this stirrup serves merely as a limit to tie the parts together and prevent undue displacements of the parts. It will be noted that the guide portion of the member C² is located at a point well down from the top of 20 the column C; that the member C² is provided with a car engaging shoulder C⁸ adapted to engage the down-stream side of the car adjacent the cushion B⁹, which car engaging shoulder is of relatively narrow width. 25 Since the car always engages the cushion, it being necessary that this width be merely sufficient to take care of slight variations in the dimensions of the car, whereas the free end of the clamp member C⁴ has a relatively 30 extended car engaging surface C⁹, which surface must be sufficient to engage the far edge of the car when the car is in engagement with the cushion no matter how wide the car may be.

35 D is a bell crank lever pivoted on the cradle frame. It has a short arm D¹ adapted to rest against an abutment D² and a long arm adapted to project outwardly away from the cradle. The arm D¹ is held against the abutment by the tension in the cable D³ which is dead ended on one end on the long arm, passes up over a sleeve D⁴ on the counterweight frame D⁵, thence down around a sheave D⁶ on the counterweight D⁷, thence 40 up over a similar sheave D⁸ back to the cradle about a guide member D⁸, thence around a guide abutment D⁹ on the left hand side of the cradle, thence up to the cradle where it is dead ended on the abutment D¹⁰. The relative position of the parts is such that when 45 the cradle is in the upright position, the tension on this cable D³ seats the bell crank lever arm D¹ against the abutments D². As the cradle rotates in a counter clockwise direction the free end of the bell crank lever D approaches the sheaves D⁴ and that part of the cable between the sheaves D⁴ and the abutment D¹⁰ also is paid out toward the sheaves D⁴. This permits the counterweight to 50 descend along its guide and the tension is maintained at all times tending to hold the bell crank lever against its stop until the end of the bell crank lever rises above the sheaves D⁴. At this time while the tension in the cable 55 is not reversed, the effect of it on the bell

crank lever is reversed and tends to rotate the bell crank lever in a clockwise direction. This is shown especially in Figure 4. There we see that the cable extends direct from the abutment D¹⁰ to the sheave D⁴ and the cable associated with the bell crank lever extends from the sheave D⁴ now in engagement with the members D⁸ and D⁹, the tension in the cable now tends to rotate the bell crank lever in a clockwise direction tending to lift the short arm D¹ away from the abutment D² to exert a tension on the clamp holding cables as will hereinafter appear. It will be noted that the angle about which the cable is bent in its engagement with the members D⁸ and D⁹ is very slight and it will be further noted that the cable will lie in a straight line out of engagement with the members D⁸ and D⁹ until just before the final dumping position is reached so that up until a point approaching the extreme end position of the cradle for dumping, there is no interference with the tension on the cable and the counter-weight is free to make its force felt upon the bell crank lever.

The clamp holding cable is shown in dash double dot lines at E. It is dead ended on the short arm of the bell crank lever D¹, passes down about a sheave E¹ on the cradle, thence up over the sheave C⁶ on the free end of the clamp, thence across the clamp over the sheave C⁵ and thence down along the downstream side of the cradle to the sheave E², thence across beneath the car to the brake pulley E³ upon which it is dead ended or stopped. A similar cable E⁴ shown for the purpose of convenience in dash lines, extends from the brake pulley E³ upwardly and outwardly to the outside of the cradle where it is wound about the series of take-up blocks E⁵ E⁶. The blocks E⁵ are fixed in position, the blocks E⁶ being supported in a stirrup E⁷ carried on a tension bar E⁸, supported by a take-up spring E⁹. Since the sole function of this cable E⁴ is to take up the slack and since no load comes upon it as a result of the dumping action, the clamps being held independent of it, this cable may be of relatively light flexible material so that the spring E⁹ required to take up the slack and draw this cable over the take up blocks may be of relatively slight strength.

The clamp is lifted by means of a clamp lifting cable which is shown for the purpose of clearness in dot dash lines at F on Figure 2. This cable is dead ended at the lower end of the clamp slide C² at a point well below the top of the car, passes up over a sheave F¹ on the cradle thence down over a sheave F² on the cradle and thence longitudinally along the cradle to a sheave F³. The various cables F one from each clamp or one from each two clamps if the cables go to each end of the cradle as is preferably the arrangement shown so that there is but

a single cable F passing over the sheave F³. This cable as will be seen in Figure 1, extends from the sheave F³ down over a sheave F⁴, thence over the sheave F⁵ to the clamp lifting carriage F⁶ on the roller ring. This clamp lifting carriage travels along the arcuate track F⁷ on the roller ring and is provided with a lug F⁸ adapted to engage an abutment F⁹. The weight of the clamps exerts tension on the lifting cable and holds the carriage lug F⁸ against the abutment F⁹. As the cradle is rotated in a counter clockwise direction, the sheave F⁵ approaches the abutment F⁹ and the clamp members are permitted to descend under the influence of gravity controlled by the rotational speed of the cradle as the sheave F⁵ approaches the carriage until the clamps are seated on the car. Thereafter further rotation of the cradle causes no further movement of the carriage along the tracks and the carriage then travels with the roller ring, lifting away from the abutment F⁹. On the return movement of the cradle the clamps are drawn up to the starting position as shown in Figure 2 by the engagement of the carriage with the abutment. As a result of this up and down action of the clamps the down movement toward the car being responsive to the weight of gravity the up movement away from the car being responsive to the drawing out of the cable between the sheave F⁵ and the stop F⁹, there is a change in the length of the clamp holding cable between its dead end point on the bell crank lever and the sheave or pulley E³ and it is to rotate this sheave or pulley and cause the cable to be always tight that the spring and take-up pulley arrangement is used. By this arrangement it will be noted that the clamp lifting cable and the sheaves and parts associated with it are all of them well below the top of the car and entirely protected by the top of the car itself against interference or variation in the flow of material from the car.

G is a cam lever having a roller G¹ adapted to engage the cam track G¹⁰. This lever by means of a link G² controls a lever G³ which in turn operates a shaft G¹² with associated levers G¹⁴, each of said levers carries a roller G⁴ engaging the brake lever G⁵. The brake band G⁶ encircles the brake drum G⁷ associated with the brake pulley E³. The spring G⁸ tends to rotate the brake lever in a clockwise direction to apply the brake band. The engagement of the roller G¹ with the cam track G¹⁰ resists the spring G⁸ and keeps the brake in the off position until the cradle has operated in an angle sufficient to insure the seating of the clamps on the car. Thereafter the roller G¹ rides off the cam, the brake is applied and then further rotation of the cradle and reversal of the power applied to the lever D exerts a tension in the clamp holding rope against the brake pulley as a

fixed abutment. This tends as the slack is taken up in the cable to cause the short end of the bell crank lever to lift away from its abutment as the slack is taken up, and the weight of the counterweight working through the long arm of the bell crank lever is sufficient to carry the load of the car and its contents. If it should happen that the weight of the car and contents should be sufficient to overcome the counterweight the worst that could happen would be that the tension in the clamp holding cable would rotate the bell crank lever to bring it back against the abutment, no further movement of the counterweight or counterweight lever being possible. On the other hand if some foreign substance should be caught between the clamp and the top of the car and should later collapse, the weight of the counterweight would cause additional rotation of the differential bell crank lever away from its abutment to take up the slack. By this arrangement the counterweight, it will be noted, is supported only on the counterweight cable and exerts no influence whatever upon the clamp raising or clamping holding cables except at the time when dumping is about to take place and when the function of the counterweight becomes essential. Other times the counterweight is free.

The use and operation of my invention are as follows:

The car is run onto to the cradle which is held in the central or loading position by the solenoid brake. The operator as soon as the car is spotted opens the circuit through the motor. This releases the solenoid brake and causes the cradle to rotate in a counter clockwise direction. As the cradle rotates away from the stop abutments the springs are free to force the transfer table to the left bringing the car into engagement with the side cushion. The movement of the cradle without movement of the clamp lifting carriage permits the clamp raising cable to be paid out and the clamps to move down toward the car. The spring take up exerting a constant tension on the clamp holding system maintains the clamp holding cables tight under initial tension as the clamps travel down. As soon as the clamps engage the car further movement of the clamp lifting carriage with respect to the roller rings ceases and further taking up of the clamp holding cables ceases. Thereafter the brake is applied on the take-up end of the clamp holding cables locking the brake sheave against rotation. Further rotation of the cradle reverses the direction in which the power is applied to the differential bell crank lever and the weight of the counterweight working through that differential lever sets up an initial holding tension on the car clamps, owing to the relative position of the lever and the sheaves associated with the counterweight guide the mechanical

advantage of the counterweight except with respect to the lever approaches its maximum toward the dumping position and there is opportunity for further rotation of the differential lever if foreign substances as coal or the like may by chance be caught and crushed between the clamp and the car.

After the car has dumped its contents the operator will reverse the motor to return the cradle toward the initial position. The cycle of operations will be reversed. First the power applied to the differential lever will be reversed to cause the short end of the lever to seat on its abutment. Then the pressure on the brake band will be released. The clamp lifting carriage will come into engagement with its stop and its movement with the cradle will be prevented thus drawing out on the lifting cable and raising the clamp above the car. The spring take-up controlled clamp holding cable will be paid out, the transfer table will be centered again in the cradle and the empty car will then be free of the clamps centered on the cradle free from the cushion and can be removed from the cradle, the next car can be handled in exactly the same manner.

I claim:

1. In a car dumper, a clamp and means for moving it toward and from a car, a clamp holding cable, an anchorage for one end thereof, a sheave about which the other end of the cable is wound, a brake adapted to hold the sheave against rotation during the dumping operation and a spring take-up adapted to rotate the sheave and maintain an initial tension on the cable during the movement toward and seating of the clamp on the car.

2. In a car dumper, a clamp and means for moving it toward and from a car, a clamp holding cable, an anchorage for one end thereof, a sheave about which the other end of the cable is wound, a brake adapted to hold the sheave against rotation during the dumping operation and a spring take-up adapted to rotate the sheave and maintain an initial tension on the cable during the movement toward and seating of the clamp on the car, the spring take-up comprising a plurality of opposed sheaves about which the cable travels beyond the first mentioned sheave and spring means for separating said take-up sheaves whereby relatively slight movement of the sheaves provides for relatively extended cable travel.

3. In a car dumper, a car holding clamp movable toward and from the car, a clamp holding rope associated with the clamp, means for taking up the slack in one end of the rope caused by clamp movement, means for positively locking the slack take-up means against movement and means associated with the other end of the rope for exerting an increased tension thereon after the

slack take up means have been locked, the slack take up means comprising a drum about which the cable is wound and a spring motor for rotating the drum to cause winding of the cable.

4. In a car dumper, a car holding clamp movable toward and from the car, a clamp holding rope associated with the clamp, means for taking up the slack in one end of the rope caused by clamp movement, means for positively locking the slack take-up means against movement and means associated with the other end of the rope for exerting an increased tension thereon after the slack take-up means have been locked, the slack take-up means comprising a drum about which the cable is wound and a spring motor for rotating the drum to cause winding of the cable, the spring motor including a cable wound about the drum, a plurality of opposed sheaves about which the cable is wound and a spring tending to separate said sheaves.

5. A car dumper comprising a cradle, a clamp extending across the car and movable up and down toward and from the car, means responsive to cradle rotation for raising the clamp against the force of gravity when the cradle is in the upright position and for causing the clamp to lower under the force of gravity as the cradle rotates, a tension lever pivoted on the cradle, an abutment against which the lever rests, a clamp holding cable extending from the lever in the direction of the abutment, encircling the clamp, a drum about which the end of the cable is wound, a brake and means responsive to cradle movement for locking the drum thereby against rotation after the clamps are seated on a car and after the cradle has made a predetermined angular excursion, a take-up cable wound about the drum and a spring motor adapted to exert a tension on said cable, to take up the slack by rotating the drum as the clamp descends toward the car.

6. A car dumper comprising a cradle, a clamp extending across the car and movable up and down toward and from the car, means responsive to cradle rotation for raising the clamp against the force of gravity when the cradle is in the upright position and for causing the clamp to lower under the force of gravity as the cradle rotates, a tension lever pivoted on the cradle, an abutment against which the lever rests, a clamp holding cable extending from the lever in the direction of the abutment, encircling the clamp, a drum about which the end of the cable is wound, a brake and means responsive to cradle movement for locking the drum thereby against rotation after the clamps are seated on a car and after the cradle has made a predetermined angular excursion, a take up cable wound about the drum and a spring motor adapted to exert a tension on said cable to
